METHOD OF MAKING A MAGNETIC CORE
Kenneth D. Beardsley, Dalton, and Edward J. Wilk,
Adams, Mass., assignors to General Electric Company,
a corporation of New York
Original application Oct. 10, 1958, Ser. No. 766,488, now
Patent No. 3,074,038, dated Jan. 15, 1963. Divided
and this application Nov. 2, 1961, Ser. No. 149,689
4 Claims. (Cl. 29—155.57)

This invention relates to a method of making a packet magnetic core. More particularly, the invention is an improvement over the packet magnetic core and method of making the same described and claimed in co-pending Treanor patent applications Serial Number 712,135, now Patent No. 3,025,483, issued January 23, 1962, and 392,205, issued November 22, 1960, as Patent Number 2,960,756 which are assigned to the same assignee as the instant patent application. By the term packet core is meant one which has a plurality of radially nested curved laminations or turns which are cut into segments with a plurality or bundle of segments of the core being simultaneously laced through the opening of a preformed electrical coil assembly.

This application is a division of co-pending parent application Serial No. 766,488, filed October 10, 1958, now Patent No. 3,074,038 issued January 15, 1963. The article described in this application is claimed in said parent application.

While the specification concludes with claims particularly pointing out and distinctly claiming the subject matter which we regard as our invention, it is believed the invention will be better understood from the following description taken in connection with the accompanying drawing in which:

FIGURE 1 is an elevation view of a magnetic core constructed in accordance with one form of our invention, and

FIGURE 2 is an exploded perspective view of the outer packet and two turn segments of FIG. 1.

The magnetic core illustrated in the drawing comprises a plurality of radially nested packets 1 to 4. The turns or lamination of the packets are spirally arranged and are cut into segments having a length of approximately one turn of the core. Preferably, the joints 10 (see FIG. 2) of all the packets are arranged on the side of the core which will be positioned in the opening of a not shown preformed electrical coil. This is so as to minimize distortion of the laminations of the core when they are being laced with an electrical coil. In the particular embodiment of the invention illustrated in the drawing the segments of the packets have a length of slightly more than one turn of the core. However, as will be obvious to those skilled in the art and is more particularly explained in the co-pending Treanor patent applications, the segments could have a length slightly less than one full turn of the core. Successive layer joints which are indicated by X marks in FIG. 1 are offset with respect to each other and the layer joints are distributed along the length of the left-hand side of the core so that the joint 10 in each packet is relatively long with respect to its thickness. A packet joint which is relatively long with respect to its thickness is not absolutely necessary but is preferred so that the disturbance of flux in one layer will not effect the disturbance of flux in an adjacent layer and also to facilitate simultaneous lacing of the cut segments of each packet with a preformed electrical coil with minimum distortion of the laminations.

In our invention, adjacent packets are separated by laminations 5 to 7 which have a length of approximately two turns of the core. Also, the innermost and outermost segments 8 and 9 of the core have a length of approxi-

2

mately two turns of the core. Prior art magnetic cores which utilize packets do not have such extra length segments between packets and on the inside and outside of the core. The special segments provide several advantages.

In our invention additional structural strength is provided in the core inasmuch as the two turn segments hold the core together. Additionally, the amount of looseness in the core is no longer critical inasmuch as the packet joints are held snugly closed by the two turn pieces even in an excessively loose core. The two turn inner piece 8 which defines the space or window opening in the core holds in the insulation on the not shown electrical coil assembly and thereby provides a good base on which to build the core. A two turn piece over each packet holds its joints closed whereas a clamping band or the like on the outside of the core would not accomplish this in the inner packets. Additionally, during lacing of the packets without the two turn segments there is a danger of dislodging the joints in previously laced packets. This is avoided when each packet is held closed by a two turn piece.

The preferred method of making the magnetic core is to take a strip of preferably grain oriented core material and wind it continuously into a plurality of radially superimposed turns on a generally rectangular shape mandrel. Winding the core strip on a rectangular shape mandrel gives them the configuration desired in the final core. After the desired number of turns are wound on the mandrel the turns are clamped, banded or otherwise held closed and the mandrel along with the wound core is placed in an annealing oven to give the turns a permanent set and relieve the stresses which were introduced therein during the winding operation. After the anneal the core and mandrel are separated and then the annealed core is cut preferably from the inside to the outside. The core could be cut by unwinding it from the outside and cutting it from the outside to the inside. However, this means that the whole core must be cut before any of the segments can be laced. If the core is cut from the inside to the outside then the packets can be laced with a preformed electrical coil without waiting until the whole core has been cut. After the inner segment 8 is cut it can be laced with the electrical coil. As the segments of the first packet 1 are cut they are set aside in a radially nested bundle. When all the segments of the first packet 1 are cut then the packet can be opened and laced with an electrical coil. Thereafter the next two turn segment 5 is laced with the electrical coil to hold the joints of the first packet 1 closed. This procedure is continued until all the packets and segments of the core are laced with the electrical coil and the last packet and whole core is finally closed by the last two turn segment 9. In our invention the single turn segments of the packets do not necessarily have to be set aside and then laced as a group but each single turn segment could be individually laced with the core right after it has been cut. However, even with such a procedure the two turn segments still provide the aforementioned advantages. Additionally, if the core has a very small window opening which provides insufficient space for the cutting tool to operate on the core from the inside to the outside, the rectangular shaped core can be expanded into say an octagon which will provide more working space inside the core for the cutting tool. However, even with such an arrangement the extra length segments between packets and on the inside and outside of the core still provides the heretofore discussed advantages of our invention.

It will be obvious to those skilled in the art that the special segments between packets and on the inside and outside of the core do not necessarily have to have a

length of two turns of the core but can be somewhat shorter or longer than two turns of the core. For instance, the extra length segments could have a length of 1½ turns of the core and the joints in successive packets could be located on opposite sides of the core. The important thing to be considered in selecting the exact length of the special segments is that they be long enough to accomplish the purposes and advantages heretofore set forth. They could be more than two turns long. However, it is preferred not to make them too long since long segments are more difficult to assemble with the electrical winding than short segments. Therefore, by the term about two turns long is meant segments which are somewhat shorter or longer than two turns long which will satisfy the above set forth requirements.

While there has been shown and described a particular embodiment of the invention, it will be obvious to those skilled in the art that changes and modification may be made without departing from the invention, and therefore, it is intended by the appended claims to cover all such changes and modifications as fall within the true spirit and scope of the invention.

What we claim as new and desire to secure by Letters Patent of the United States is:

1. A method of making a curved magnetic core which comprises winding a strip of magnetic core material into a core form having a plurality of radially superposed turns, clamping said core form, annealing said core form to give said turns a permanent set, cutting said strip from the inside to the outside, without unwinding, into groups of successive approximately single turn length segments which are alternated with approximately two turn length segments, and lacing said groups and two turn segments in the order cut with a preformed electrical coil.

2. A method of making a curved magnetic core which comprises winding a strip of magnetic core material into a core form having a plurality of radially superposed turns, clamping said core form, annealing said core form to give said turns a permanent set, cutting said strip from the inside to the outside without unwinding alternately

5 into an approximately two turn length segment and then a group of approximately single turn length segments, radially nesting each group of single turn segments into a packet, and alternately lacing each two turn segment and simultaneously the single turn segments of each packet in the order cut with a preformed electrical coil.

3. A method of making a curved magnetic core which comprises winding a strip of magnetic core material into a core form having a plurality of radially superposed turns, clamping said core form, annealing said core form 10 to give said turns a permanent set, cutting said strip to provide a segment having a length of approximately two turns of said core, then cutting said strip into a plurality of segments having a length of approximately one turn of said core, then cutting another segment having a length of approximately two turns of said core, again cutting a plurality of segments of approximately one turn in length and another segment of approximately two turns in length, and lacing said cut segments with a preformed electric coil, by first lacing the smallest of said two turn segments, then lacing all of the smallest of said plurality of one turn segments, then lacing the next largest of said two turn segments, then lacing all of the next largest of said plurality of one turn segments and finally lacing the largest of said two turn segments.

4. A method of making a curved magnetic core as claimed in claim 3 in which said strip is cut from the inside of said core to the outside without unwinding and said segments are laced with said preformed electric coil in the order in which they were cut.
